Primary Examiner — Selina Sikder(74) *Attorney, Agent, or Firm* — Kilpatrick Townsend & Stockton, LLP(57) **CLAIM**

The ornamental design for a remote control, as shown and described.

DESCRIPTION

FIG. 1 is a front isometric view of the remote control showing our new design;

FIG. 2 is a back isometric view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing button indicia are for illustrative purposes only and form no part of the claimed design.
